UNITED STATES PATENT OFFICE.

HERMAN L. WELCH, OF EL CENTRO, CALIFORNIA.

COPY-HOLDER.

1,307,945.

Specification of Letters Patent. Patented June 24, 1919.

Application filed June 21, 1917. Serial No. 176,189.

To all whom it may concern:

Be it known that I, HERMAN L. WELCH, a citizen of the United States, residing at El Centro, in the county of Imperial and State of California, have invented certain new and useful Improvements in Copy-Holders; and I do hereby declare the following to be a full, clear, and exact description of the invention, such as will enable others skilled in the art to which it appertains to make and use the same.

This invention relates to copy holders, and more particularly to a type of copy holder adapted to be arranged upon the top of a desk, such for instance as desks to which typewriters may be rigidly secured.

It is one of the objects of the present invention to provide a copy holder which may be conveniently arranged upon the top of a typewriter desk in such manner that the copy may be held conveniently in a position above and adjacent the typewriter on the desk.

It is a further object of the invention to provide a copy holder which may be connected to the desk in such manner that the carrier of the copy holder may be conveniently turned by the operator from a position immediately above the typewriter as when the notes are being transcribed, to a position swung out of the way to permit the ready removal or insertion of paper at the typewriter.

Another object of the present invention is to provide a copy holder which may be connected to the top of a desk by means of a fastening device which is adapted to be yieldably mounted on the edge of the desk and engage a contiguous portion of the copy holder to prevent the latter from tilting when the copy carrier of the holder is swung into a lateral position with relation to the base or support of the holder in an unbalanced position thereto.

It is another object of the invention to provide a copy holder of simple, inexpensive and readily adjustable parts which are capable of being totally disassembled to enable the parts to be compactly arranged for storage or shipment, and which further provides for the ready and relative adjustment of the parts as may be requisite for the adaptation of the copy holder to the given desk upon which it may be arranged and to facilitate the positioning of the copy with relation to the typewriter on the desk.

An important object of the present invention is to provide for the ready indication of the line or lines at about the zones along the notes or copy being transcribed, so that the operator may work with rapidity and facility in transcribing.

With these and other objects in view one embodiment of my invention is described in the following specification and illustrated in the accompanying drawings, in which latter:

Figure 1 is a front elevation of the copy holder as applied to the top portion of a desk with the parts adjusted in juxtaposition to support a copy over a typewriter, parts of the device being broken away.

Fig. 2 is a detail perspective view of a portion of the device illustrating the construction of the slide.

Fig. 3 is a detail perspective view of the detachable clip for fastening the base detachably and without extraneous fastening means to the top of the typewriter desk.

Fig. 4 is an end view of the detached copy carrier of the device.

Fig. 5 is a plan view thereof.

Fig. 6 is a detail view of the finger actuated mechanism for actuating the line indicator.

Fig. 7 is a plan view of Fig. 6.

Fig. 8 shows another form of feed clamp.

Fig. 9 is a detail of the base structure.

The copy holder here shown comprises an upright or column 2 of suitable proportions and material, and which is preferably tubular to provide for the reception of an upper section 3 which has its lower portion turned cylindrically so as to be rotatively mounted in the socket or lower section 2. The upper portion or section 3 of the upright is adapted to receive a suitable type of slide 4 which is provided with a slideway 5 having a cross sectional contour corresponding to the cross section of the top section 3, such for instance being indicated as of dove-tail outline. The upright 2 is adapted to be held in vertical position through any suitable form of base or supporting arrangement, and this preferably consists of a foot rod 6 of suitable diameter which is slidably fitted in an aperture 6' formed therefor in the lower portion of the upright 2, the foot rod 6 being provided adjacent its ends with cushion or rubber rings 7 which may be mounted upon slide rings 7', these being adjustable longitudinally along the foot bar 6 in accordance with the shape

and size of the table or desk top upon which the support may be mounted. The longitudinal adjustment of this rod provides for convenient mounting of the stand upon the desk 5 top. The slideable cushion members 7 may be removable so as to permit the withdrawal of the foot bar 6 from the standard 2 when it is desired to disassemble and pack or store the device for shipment or other purposes. 10 Projecting normally from the lower portion of the base 2 there is provided a transverse rest or foot member 8, the inner end of which may be securely fastened within the lower part of the upright 2, and, as shown, 15 the adjustable foot bar 6 may pass through the inner end of the rest 8. At the outer end of the latter there is provided a suitable fastening device as a thumb screw and nut 9, whereby there may be clamped to the lower 20 side of the rest 8 an extension 10. Either or both of these members 8 and 10 may be longitudinally slotted to provide for the telescopic or longitudinal adjustment of one with relation to the other. When the copy 25 holder is to be arranged upon a typewriter desk, for instance, having a central leaf C which may be provided with a typewriter indicated at T in diagrammatic lines, and which may have in the plane of the central 30 section C the end leaf L, the foot bar 6 of the copy holder is disposed parallel to the contiguous edge of the typewriter top or leaf L where it approaches the edge of the central section of the top at C. Then the extensible rest is adjusted by the outward movement of its section 10, for instance, until the latter alines with the adjacent outer edge of the leaf whereupon these may be detachably secured to each other through means of a 35 suitable plate. I prefer to utilize a fastening device of such a character that it will hold the rest or base member 8-10 of the upright 2 to the top of the desk at L without injuring the latter or requiring the attachment thereto of screws or other fastening means, and to accomplish this I provide a resilient clamp in the form of a ring 11 which has tangentially extending substantially parallel arms 12 which have perpendicularly bent ends 13, these latter being 40 adapted to overlap upon the top of the extension 10 and below the projecting portion of the leaf or top L of the desk as shown in Fig. 1. 45

50 The slide 4, which is adapted to be secured at any suitable elevation along the section 3 of the upright, is provided with a simple form of fastening device as an L-shaped hook 5 which has a threaded shank extending forwardly through the slide to receive a wing nut 5^a whereby the rear hooked end of the clamping device may be drawn snugly against the adjacent section 3 whereby the slide 4 is locked in the desired position. 55

60 This slide is provided in its front portion

with a longitudinally extending slideway 4^a which is disposed normally to the slideway 5, and in this slideway there is transversely adjustable as to the upright 2 an arm 15 having a suitable cross section to fit in the slideway 4^a, the latter being shown as of dove-tail cross section in this instance. One end of the arm 15 is adapted to receive and support a copy receiving device hereinafter called the copy carrier, designated as including a frame 70 16 of suitable material, design and construction, and which may be provided on its rear surface with a suitable guide comprising a pair of bars 17, for instance, to receive the inserted end of the arm 15. The carrier 16 75 is disposed in a substantially perpendicular or vertical position and may be inclined slightly from the bottom upwardly and rearwardly as shown in Fig. 4 to conveniently support the note paper or copy in position 80 before the operator. There may be provided, attached to the upper end of the frame 16, a flat shelf 18 of suitable proportions and design whereon may be secured the back of a stenographer's note book during transcription. Upon the lower end of the frame 16 there is provided a horizontal and slightly 85 upwardly extending shelf 19. It will be seen that by providing for horizontal adjustment of the arm 15 in the slide 4 the copy carrier 90 16 may be adjusted toward and from the upright 2 as may be desired, and may be disposed in suitable vertical position by adjustment of the slide 4 along the upper section 3 of the upright 2. Another important feature 95 100 is that by providing a section as 3 on which the slide 4 is mounted with capacity for rotation as to the lower portion of the upright 2, the operator may grasp the arm 15 of the device and swing this rearwardly or forwardly to provide for ready and easy adjustment of the copy upon the carrier 16, and when the latter is adapted to be arranged in position over a typewriter the operator may swing the arm 15 to the rear 105 110 so as to remove the carrier 16 to permit the ready insertion of paper into the typewriter, and removal therefrom. 115

Another important feature of my invention consists in the provision of means 115 whereby during the transcription of notes from the copy to the machine the approximate area or zone of the lines on the copy which is being transcribed can be indicated with facility and greatly increase the rapidity of transcription by the operator. To that end I have provided an indicator comprising a pointer 20 in the form of a cylinder wire, for instance, which is disposed in a horizontal plane across the front 120 of the carrier frame 16, one end of the pointer being secured in a slide 21 which is slidably mounted upon the frame in any suitable manner. As here shown, the slide 125 is in the form of a block having its longi- 130

tudinal edges recessed, as shown in Fig. 4 at 22, to receive a pair of parallel upright wires 23 between which the block slides vertically from the top shelf 18 downwardly 5 toward the shelf 19 of the carrier. To control the movement of the block 21 there may be attached to it at its opposite ends an endless cord 24 which passes over a suitable guide 25 mounted on the top 18 of the 10 carrier, this latter being provided with apertures 25' through which the cord may travel, and the lower end of the endless cord 24 is directed around a suitable guide as 26 secured to the lower side of the bottom shelf 19. The plane of the loop of the endless band or belt 24 is shown as perpendicular to the front plane of the carrier 16, and the rear stretch of the belt passes between gripping jaws of suitable means for 15 gripping and moving the endless belt in step by step operation. This actuating means is shown as comprising a lever 27 pivoted at 28 upon a convenient portion of the frame 16 and disposed at the rear side thereof, 20 one end of the lever carrying a pivoted finger key 29, Figs. 1 and 6, which projects laterally from one side of the frame of the carrier so as to be within convenient reach of the operator. Connected to one end of 25 the finger key or lever 29 there is provided a link 30 which extends parallel along the lever 27 and is connected at its opposite end to an upright jaw 31 which is pivoted at 32 to the contiguous end of the lever 27. 30 This latter is provided with an offset jaw 27' in the plane of the face of the jaw 31. In operation when the operator depresses the lever 29 the first or initial movement is transmitted through the link 30 to the pivoted jaw 31 and this is swung against the intervening cord 24 whereby this latter is pressed against the jaw 27'. Thereafter continued downward movement of the pivoted key 29 and the adjacent end of the lever 27 causes the cord to be lifted by the pinching jaws 31 and 27' a limited and suitable degree. To normally hold the lever 27 in suitable position, this latter is connected by a spring 33 to a convenient and fixed portion 40 of the carrier frame 16, as shown in Fig. 1, the spring compressing under pressure of the key lever 29 and expanding again when pressure is removed from the key, thus returning the parts to normal position. 45

From the foregoing it will be seen that I have provided a copy holder which is readily adjustable to the top of a suitable desk, table or other support, and may be clamped to the same without in any way mutilating or injuring the desk or table structure or surface, and I have provided a holder adapted to be so adjusted as to support the copy to be transcribed in a position above the type-writer, means being provided for prevent-

ing the overbalanced weight carried by the upright 2 from tilting the carrier or holder. I have also provided means whereby the operator may readily determine the area or portion of the notes being transcribed, and which means may be operated with convenience and rapidity by the operator. 70

In the form of the clamp shown in Fig. 8 the lever 27 carries a fixed part 31 and opposed to it is a clamp jaw 27^a pivoted at 27^b on the lever. The jaw grips when the lever moves up and freely releases on the downward movement thereof.

What I claim is:

1. A copy holder, adapted for attachment 80 to a desk, comprising an upright, a copy carrier attached thereto, a base for the upright having rests, one of which is longitudinally adjustable in said base and adapted to be arranged parallel along one edge of 85 the desk and the other of which is adjustable and adapted to extend transversely thereto to the side of the desk, and means for embracing the transverse rest to the edge of the desk and prevent tilting. 90

2. A copy holder, adapted for attachment to a desk, comprising an upright, a copy carrier attached thereto, a base for the upright having adjustable rests, one of which is within the side planes of the upright and is adapted to be arranged parallel along one edge of the desk and is adjustable longitudinally with respect to the upright and the other to extend transversely thereto and comprises a slotted section attached to 95 the base and an extensible section connected thereto, and means for securing the transverse rest to the edge of the desk to prevent tilting. 100

3. In a copy holder, an upright comprising a socket member and a rotary post, a copy carrier thereon, a foot bar adjustably transversely in said member, and an extensible rest connected to the latter perpendicularly to the foot bar and forming a 110 support lateral to the bar. 105

4. In a copy holder, an upright comprising a socket member and a rotary post, a copy carrier thereon, a foot bar adjustably mounted in said member, an extensible rest 115 connected to the latter and perforated at its end to receive the foot bar.

5. In a copy holder, an upright comprising a split socket member and a rotary post, a copy carrier non-rotatively and slidably 120 mounted on said post, a foot bar adjustably mounted in said member, an extensible rest connected to the latter in and interlocking with the foot bar, and a resilient clip for embracing said rest and the desk top to 125 hold the upright against tilting.

6. In a copy holder, an upright including a socket member, and a foot bar therefor, slidably passing through the base of said member, having cushions; a lateral, extensi- 130

ble rest, and a clip having arms to embrace said rest and the adjacent support.

7. In a copy holder, an upright comprising a socket member carrying a rotary post, 5 and a foot bar therefor slidably passing through the base of the member, having adjustable cushions on opposite sides of the

member, one of which cushions is removable to permit the removal of said bar from the upright, and means adjustable laterally from 10 the bar for attachment to the edge of a support to prevent the holder from tilting.

In testimony whereof I affix my signature.
HERMAN L. WELCH.
